UNITED STATES PATENT OFFICE.

FREDERICK L. RE QUA, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT CONTROLLER.

Application filed May 27, 1921. Serial No. 473,002.

To all whom it may concern:

Be it known that I, FREDERICK L. RE QUA, a citizen of the United States, residing at Milwaukee, in the county of Milwaukee and State of Wisconsin, have invented new and useful Improvements in Circuit Controllers, of which the following is a full, clear, concise, and exact description, reference being had to the accompanying drawing, forming 10 a part of this specification.

This invention relates to circuit controllers and is particularly applicable to controllers for single phase motors although certain features of the invention may be 15 advantageously used in other relations.

To facilitate starting of single phase motors, the same are usually provided with an auxiliary winding to be included in circuit during starting and excluded from circuit 20 during running and the present invention has among its objects to provide an improved and simplified controller for effecting the necessary starting and running connections for such motors.

Another object is that of providing a controller of the aforesaid character having a 25 push button operating member adapted when moved in one direction to provide starting connections for the motor and adapted when released to permit automatic 30 establishment of running connections.

Another object is to provide a push button controller of the character stated having electro-magnetic retaining means adapted 35 to be de-energized automatically or at will, said controller also having mechanical tripping means associated therewith adapted for push button actuation, and is adapted to be tripped by push button actuated 40 tripping means.

Various other objects and advantages of the invention will hereinafter appear.

The accompanying drawings illustrate one embodiment of the invention which will 45 now be described; it being understood that the controller illustrated is susceptible of embodiment in other forms without departing from the scope of the appended claims.

In the drawings,
50 Fig. 1 is a longitudinal sectional view of a controller embodying the invention, the movable contact elements being shown in open position.

Fig. 2 is a similar view illustrating the 60 movable contact elements in starting relation;

Figs. 3, 4 and 5 are detail perspective 65 views of certain of the parts illustrated in Figs. 1 and 2;

Fig. 6 is a vertical sectional view taken 70 substantially on line 6—6 of Fig. 1; and

Fig. 7 is a diagrammatic view illustrating 75 the circuit connections of the controller.

The controller illustrated includes stationary contacts 10 and 11 and movable contact elements 12 and 13, the former contact element carrying insulated contacts 14 and 15 to co-operate with stationary contacts 10 and 11 respectively and the latter contact element carrying an insulated contact 16 to 75 co-operate with contact 14. Said contact elements, as hereinafter set forth, are provided with a lost motion connection therebetween and the same are movable against the action of a spring 17 by a push button operating member 18. An electro-magnetic winding 19 is provided for maintaining contact element 12 in closed position, said winding having an armature member 20 which is pivotally secured to contact element 12 and is adapted to be tripped by a pair of 80 dogs 21 operable by push button 22.

More specifically the controller includes 85 a supporting plate 23 and an insulating base 24 arranged below said plate secured thereto by screws 25 passing through tubular insulating spacers 26 of suitable length. Stationary contacts 10 and 11 are mounted on the upper face of base 24 adjacent the 90 right hand end thereof and the same extend upwardly at right angles to the face of said base and have their upper ends reflexed to provide contacting portions for contacts 14 and 15. Contacts 10 and 11 are each provided with a terminal member 27, 100 said terminal members extending upwardly at right angles to base 24 and being provided with binding screws 28 at the upper ends and having their lower ends secured to base 24 by screws 29. Supporting plate 23 is 105 formed to provide spaced downwardly extending lugs 30 and the same is also provided with openings on the opposite sides of said lugs to receive the push buttons 18 and 22. Lugs 30 are provided with openings 110 adjacent their lower ends to receive a pivot

pin 31 which serves to support contact elements 12 and 13 and dogs 21.

Contact element 12 is arranged for mounting between lugs 30 and as shown in Fig. 3 the same includes a sheet metal stamping 32 provided with parallel upstanding arms 33 having their right ends connected by a portion 34. Arms 33 are provided with openings 35 intermediate their ends to receive pivot pin 31 and with openings at the left ends thereof to receive a pivot pin 36 for armature 20. Said arms are also provided with slots 37 on opposite sides of the openings 35 for a purpose hereinafter set forth. Connecting portion 34 is provided with an opening 38 to receive spring 17 and the same projects beyond arms 33 and is bent upwardly to form a seat for an insulating member 39. Insulating member 39 is secured to portion 34 and contacts 14 and 15 are secured to opposite ends of said member said contacts being U-shaped and being provided with flexible leads 40 to be secured to terminals on base 24.

25 Contact element 13 as shown in Fig. 3 includes a sheet metal supporting member 41 provided with parallel upstanding arms 42 and a connecting portion 43 intermediate the ends of said arms. Arms 42 are spaced to straddle lugs 30 of plate 23, and the same are provided with openings intermediate their ends for receiving pivot pin 31. Connecting portion 43 has an insulating member 44 secured to the under side thereof and contact 16 is secured to a projecting end portion of said member and is provided with a flexible lead 45 to be secured to a terminal on base 24. Push button 18 is pivotally mounted on a pin 46, said pin being arranged within the left hand slots 37 of arms 33 and being fixed to the left hand ends of arms 42. The upper end of spring 17 passes through opening 38 in supporting member 32 and is attached to a pin 47 arranged within the right hand slots 37 of said member and secured to the right hand ends of arms 42. The lower end of spring 17 passes through an opening in insulating base 24 and is attached to a pin 50 which is seated in a recess in the lower face of base 24 as best shown in Fig. 1.

Electro-magnetic winding 19 is provided with a laminated core 52 which is secured to a sheet metal frame 53 and is preferably provided with a shading coil 52a. Frame 53 is U-shaped in cross section, the side walls thereof being arranged on opposite sides of winding 19 and having their upper ends bent inwardly to provide portions for securing to the lower face of supporting plate 23 by screws 54. Armature member 20 is also U-shaped in cross section, the same being so proportioned that the side walls thereof overlap the side walls of supporting frame 53. As shown in Fig. 5 the front

wall of said armature member is formed to provide hooked projections 55 for receiving pivot pin 36 and forwardly extending projections 56 to be engaged by tripping dogs 21. The front wall of said armature 70 is also formed to provide a shoulder 57, said shoulder being arranged to engage the under side of core 52 when contact element 12 is moved into closed position. Armature 20 is biased to move away from core member 52 by a coil spring 58, said spring having one end fixed within an opening 58a in one of the arms 33 of member 32 and its opposite end arranged to engage the left hand face of armature 20. As shown in Figs. 1 and 2 the tripping dogs 21 are pivoted intermediate their ends on supporting pin 31 the left hand ends thereof being arranged below projections 56 and the right ends thereof being connected to push button 22 by bracket 80 members 59 best shown in Fig. 6.

From the foregoing it will be observed that spring 17 normally holds contact elements 12 and 13 in the positions shown in Fig. 1. Assuming now the push button 18 is depressed it is apparent that during downward movement thereof contact element 13 will move in a counter-clockwise direction against the action of spring 17 and independently of contact element 12, the latter element being frictionally held in the position shown in Fig. 1. Upon engagement of contact 16 with contact 14, pin 46 abuts the lower end of the left hand slots 37 in supporting member 32 and upon continued downward movement of push button 18, contact elements 12 and 13 are moved simultaneously into the position shown in Fig. 2. Referring to Fig. 7 it will be observed that stationary contacts 10 and 11 are connected to supply lines L and L' and it is assumed that the running winding of the motor is connected across contacts 14 and 15 while the starting winding is connected across contacts 15 and 16. Thus upon movement of contact elements 12 and 13 to the positions shown in Fig. 2 both of the windings of the motor will be energized. Winding 19 is connected across contacts 14 and 15 and immediately upon movement of contact element 12 into closed position the same is energized and attracts armature 20 to hold element 12 in closed position. Assuming now that push button 18 is released, spring 17 moves contact element 13 in a clockwise direction independently of contact element 12 to disengage contact 16 from contact 14 for exclusion of the starting winding of the motor. Contact element 12 remains in closed position subject to low voltage conditions in winding 19 and under such conditions spring 58 moves armature member 20 out of latching engagement with core 52 whereupon contact elements 12 and 13 return to 100 positions shown in Fig. 1 with a snap action 110 115 120 125 130

- under the action of spring 17. The motor can also be stopped at any time by depression of push button 22, depression of said button serving to move the left hand ends 5 of dogs 21 upwardly under projections 56 of armature 20 to trip the latter. Obviously the winding 19 can be arranged either in shunt as shown or in series in the motor circuit and one or more control switches 10 can be provided for de-energizing the same.
- The aforescribed controller is provided with a rectangular enclosing casing 60, said casing being provided with an opening 61 at one end thereof to receive the required 15 leads and having a plurality of lugs 62 adjacent the upper edge thereof to engage the under side of supporting plate 23. Supporting plate 23 is secured to lugs 62 by screws 63 and the same is also tapped to 20 receive screws 64 for securing of a face plate 65 above the same.
- While the aforescribed controller has been shown and described in connection with a single phase motor having an auxiliary 25 starting winding, it is apparent that the same is also adapted for use with other types of motors. Also it is apparent that the contacts can be arranged in other ways to suit other control requirements.
- 30 What I claim as new and desire to secure by Letters Patent is:
1. In a motor controller, in combination, a plurality of stationary contacts, a plurality of pivoted contact members, one being 35 adapted to co-operate with said stationary contacts to establish running connections and the other being adapted to make contact with said former member and to co-operate therewith to establish starting connections, electro-magnetic means for retaining 40 said former contact member in closed position, a pair of push buttons arranged on opposite sides of the pivots of said contact members one being adapted when de- 45 pressed to effect sequentially contact between said members and between said former member and stationary contacts and when released to permit separation of said members and means associated with the 50 other of said push buttons for tripping said retaining means.
  2. In a motor controller, in combination, a plurality of stationary contacts, a plurality of movable contact members pivoted 55 concentrically, one being adapted to co-operate with said stationary contacts to establish running connections and the other being adapted to make contact with said former member and to co-operate there- 60 with to establish starting connections, electro-magnetic means for retaining said former member in closed position and a pair of push buttons, one being arranged to one side of the pivot of said members and being 65 operatively connected thereto whereby its depression effects establishment of said starting connections and its release permits disengagement of one member from the other for establishment of running connections and means associated with the other 70 of said push buttons for tripping said retaining means to effect interruption of running connections.
  3. In a motor controller, in combination, 75 a plurality of stationary contacts, a plurality of movable contact elements one having contacts co-operating with said stationary contacts to establish running connections and the other being adapted to co-operate with certain of the contacts of said former element to establish starting connections, a spring biasing both of said elements for circuit interruption, a push button operatively connected to said elements 80 and adapted when depressed to effect circuit closing operation of both elements and when released to permit circuit interrupting operation of one element independently of the other, and electromagnetic means for releasably maintaining said last mentioned 85 element in circuit closing position.
  4. In a motor controller, in combination, 90 a supporting member, a plurality of stationary contacts carried thereby, a plurality of contact elements pivoted to said supporting member, one of said elements being adapted to co-operate with said stationary contacts to establish running connections and the other being adapted to contact with said former element and to co-operate therewith to establish starting connections, electromagnetic means associated 95 with said former element for maintaining the same in circuit closing position and a pair of push buttons, one being adapted to trip said retaining means and the other being operatively connected to said contact elements and being adapted when depressed to effect circuit closing movements of said elements sequentially and when released to 100 permit circuit interrupting movement of one of said elements while the other is maintained in circuit closing position by said electromagnetic means.
  5. In a motor controller, in combination, 105 a plurality of stationary contacts, a plurality of contact elements pivoted concentrically and one having contacts co-operating with said stationary contacts for the control of running connections and the other having a contact co-operating with a contact of the former element for the control of starting connections, a lost motion connection between said elements, a reciprocable push button adapted when depressed to maintain both of said elements in closed position and when released to permit opening of said latter element independently of the former, an armature member pivoted to 110 said former element and a winding for at- 115
  6. In a motor controller, in combination, 120 a plurality of stationary contacts, a plurality of contact elements pivoted concentrically and one having contacts co-operating with said stationary contacts for the control of running connections and the other having a contact co-operating with a contact of the former element for the control of starting connections, a lost motion connection between said elements, a reciprocable push button adapted when depressed to maintain both of said elements in closed position and when released to permit opening of said latter element independently of the former, an armature member pivoted to 125 said former element and a winding for at- 130

tracting said armature to maintain said element in closed position subject to release under predetermined electrical conditions.

6. In a motor controller, in combination, 5 a plurality of stationary contacts, a plurality of contact elements pivoted concentrically and one having contacts co-operating with said stationary contacts for the control of running connections and the other having a contact co-operating with 10 a contact of the former element for the control of starting connections, a lost motion connection between said elements, a reciprocable push button adapted when de-

pressed to maintain both of said elements 15 in closed position and when released to permit opening of said latter element independently of the former, an armature member pivoted to said former element, a winding for attracting said armature to maintain 20 said element in closed position subject to release under predetermined electrical conditions, and means including a push button for tripping said armature.

In witness whereof, I have hereunto sub- 25 scribed my name.

FREDERICK L. RE QUA.
